UNITED STATES PATENT OFFICE.

JACOB F. MARTIN, OF BELLEVUE, OHIO.

AUTOMOBILE-BUFFER.

1,395,925.

Specification of Letters Patent.

Patented Nov. 1, 1921.

Application filed October 29, 1920. Serial No. 420,501.

To all whom it may concern:

Be it known that I, JACOB F. MARTIN, a citizen of the United States, residing at Bellevue, in the county of Huron and State of Ohio, have invented certain new and useful Improvements in Automobile-Buffers, of which the following is a specification.

My invention relates to improvements in automobile buffers, and more particularly to 10 that class or type which are designed to be attached to and carried by the front and rear portions of the motor vehicle for the purpose of protecting the latter and also cushioning the shock or impact due to coming into contact with another vehicle, pedestrian, or other object.

The primary object of the invention is to provide a generally improved buffer of this 20 class, which will be exceedingly simple in construction, cheap of manufacture, and efficient in use.

A further object is to provide an improved one-piece buffer-bar of improved form including open end loops terminating in inwardly extending attaching arms of ogee form.

A further and very important object is the provision of improved buffer-bar carrying, supporting and cushioning supplemental spring members particularly designed and adapted for attachment to the scroll portions of spring members of the scroll elliptic type whereby such main and supplemental spring or attaching members are 35 adapted to coöperate with each other in giving added strength and resiliency to the attachments, as well as reducing the liability of breakage or damage to the springs to a minimum.

40 A still further and very important object is the provision of an improved buffer-bar attaching and cushioning device which may be readily and quickly attached to and detached from springs of this general type.

45 With the above mentioned and other ends in view, the invention consists in the novel construction, arrangement and combination of parts, hereinafter described, illustrated in one of its embodiments in the accompanying 50 drawings, and particularly pointed out in the appended claims.

Referring to the drawings, forming a part of this specification, Figure 1, is a fragmentary top plan view of the improved buffer-bar and its supplemental spring at-

taching members, the middle or median portion of the buffer-bar being broken away and the end loops drawn together for the purpose of illustration.

Fig. 2, a side elevation of the improved buffer-bar and its attachments as applied to springs of the "scroll elliptic" type.

Fig. 3, a fragmentary front elevation of the improved buffer-bar and the improved supplemental spring attaching members and 65 clamps for attaching the latter to the scroll portions of the elliptic springs.

Similar numerals of reference designate like parts throughout all the figures of the drawings.

70 The improved buffer-bar is of the "one-piece" type and comprises a single length of material forming the main body portion 1, of the buffer-bar, and having the ends thereof bent upon themselves forming open end loops 1^a, said loops terminating in inwardly extending spring arms of general ogee form, the inner ends of said arms 1^b, terminating in attaching members 1^c.

75 As a means of suitably mounting and attaching the ends 1^c, of the buffer-bar to the scroll portion of springs of the scroll elliptic type whereby the latter will coöperate with the former in giving added strength and resiliency to the parts, the invention includes a pair of buffer-bar supporting supplemental spring members 2, having curved portions 2^a, conforming to the general contour of the scroll portion 3^a, of the elliptic spring 3, said curved portion 2^a, terminating at its end in a loop-eye 2^b, adapted to receive and contain the sleeve of the upper spring and between the shackle or link members 4, as illustrated most clearly in Fig. 2 of the drawings.

80 As a means of attaching the supplemental spring or bracket members 2, to the scroll portions 3^a, of the springs 3, suitable clamping members are provided, said clamping members, in the present instance, comprising U-shaped clamps 5, extending over the edges of the parts 2 and 3^a, said clamps having their sides threaded and extending through suitable openings in clamp plates 6, and provided with clamping nuts 6^a.

85 As a means of attaching the ends 1^c, of the buffer-bar to the upper ends of the supplemental spring or bracket members 2, the latter are provided with suitable openings adapted to register with suitable openings 90 100 105 110

in the ends of the buffer-bar and to receive and contain suitable attaching bolts 7, provided with suitable clamping nuts 7^a.

While the improved buffer-bar is particularly designed and adapted for use as a rear buffer-bar in connection with this type of springs frequently employed at the rear of automobiles, it will at once be apparent that the same is equally well adapted for use as a front buffer-bar in connection with similarly shaped springs when used at the front or similarly shaped chassis side bars.

Having thus described one of the embodiments of my invention, without having attempted to set forth all the forms in which it may be made, or all the modes of its use, what I claim and desire to secure by Letters Patent, is,--

1. An automobile buffer, comprising a buffer-bar, buffer-bar supporting members attached to the ends thereof and comprising supplemental spring members conformed and attached to the depending scroll portions of the upper vehicle springs and terminating in loop-eyes engaging the sleeves of the springs between the shackle members thereof, and clamping members connecting said supplemental and main springs whereby said buffer-bar will be supported and cushioned by said upper vehicle springs.

2. An automobile buffer, comprising a buffer-bar, buffer-bar supporting members attached to the ends thereof and comprising supplemental spring members conformed to and attached to the depending scroll por-

tions of the upper vehicle springs and terminating in loop-eyes engaging the sleeves of the springs between the shackle link members thereof, and clamping members connecting said supplemental and main springs whereby said buffer-bar will be supported and cushioned by said upper vehicle springs.

3. An automobile buffer, comprising a buffer-bar having open end loops terminating in attaching arms, supplemental members conformed and attached to the depending front portions of the upper vehicle spring member and extending upwardly in front of the latter, clamping means connecting said supplemental members to said depending portions of said vehicle spring members, and means for attaching said buffer-bar attaching arms to said supplemental buffer-bar supporting members.

4. In an automobile buffer, the combination with vehicle springs of the scroll elliptic type, including sleeve and shackle members; of supplemental spring members conformed to the scroll portions of said spring members and terminating in eye portions extending over the sleeve members between the shackle members thereof, U-shaped clamp members extending over and clamping said supplemental and scroll elliptic vehicle springs together, and a buffer-bar secured to said supplemental spring members above said U-shaped clamps.

In testimony whereof I have affixed my signature.

JACOB F. MARTIN.
